UNITED STATES PATENT OFFICE.

THOMAS F. MULLIGAN, OF FORT WAYNE, INDIANA, ASSIGNOR TO S. F. BOWSER & COMPANY, INC., OF FORT WAYNE, INDIANA, A CORPORATION OF INDIANA.

APPARATUS FOR FILLING OIL-CANS.

1,112,082.

Specification of Letters Patent. Patented Sept. 29, 1914.

Application filed January 15, 1909. Serial No. 472,403.

To all whom it may concern:

Be it known that I, THOMAS F. MULLIGAN, a citizen of the United States, residing at Fort Wayne, in the county of Allen and State of Indiana, have invented certain new and useful Improvements in Apparatus for Filling Oil-Cans, of which the following is a specification.

This invention relates to improvements in portable apparatus for filling oil cans, and the primary object of the same is to provide an improved device of this character for filling oil cans or other receptacles, and which will automatically cut off or stop the supply of oil when the can or receptacle is filled to prevent spilling or wasting the oil.

A further object is to provide an improved normally closed discharge nozzle which is adapted to be adjusted by the can or receptacle when the latter is properly positioned to be filled, and improved means for permitting the oil to pass the outlet to be discharged back into the tank when the can is filled or when no can or receptacle is present under the nozzle, thereby preventing waste of oil.

A further object is to provide an improved device of this character which will be simple, durable and cheap in construction, and effective and efficient in operation.

To the attainment of these ends and the accomplishment of other new and useful objects, as will appear, the invention consists in the features of novelty in the construction, combination and arrangement of the several parts hereinafter more fully described and shown in the accompanying drawing illustrating the embodiment of the invention, and in which:

Figure 1 is an elevation partly in section of an improved device of this character constructed in accordance with the principles of this invention. Fig. 2 is an enlarged detail sectional view of the discharge nozzle and valve showing the latter in one of its positions. Fig. 3 is a detail view similar to Fig. 2, showing a modified form of the discharge nozzle and valve. Fig. 4 is an enlarged detail sectional view of the discharge nozzle and valve with the latter in position to permit the fluid to pass the discharge nozzle and to reenter the tank. Fig. 5 is an enlarged detail sectional view of the pump for forcing the liquid from the tank. Fig. 6 is an enlarged detail sectional view partly

in elevation of the support and lifting mechanism for the oil can. Fig. 7 is a detail top plan view of the discharge nozzle.

Referring more particularly to the drawing, and in the present exemplification of the invention, the numeral 10 designates the tank for containing the oil to be dispensed, and which tank may be of any desired size and configuration and constructed of any suitable material. Located within the tank 65 is a pump cylinder 11 which has an opening 12, preferably at the bottom thereof and which opening serves as an inlet and an outlet for the cylinder. A tubular member 13 projects into the tank through an outlet 70 opening in the top 14 thereof and is provided adjacent one extremity with a valve casing 15, which latter is provided with valve seats 16, 17. Connected to and communicating with the casing 15 is a tubular member 18 which extends to a point in close proximity to the bottom of the tank 10. Valves 19 and 20 are provided to coöperate with the respective valve seats 16 and 17, and a communicating passage 21 is provided 80 between the pump cylinder 11 and the casing 15, preferably above the valve seat 17. The valve casing 15 is also provided with a valve seat 22 with which the valve 20 coöperates in a manner to be set forth.

The tubular member 13 extends for any desired distance above the top of the tank and is connected by means of a tubular connection 23 to a similar upright tubular member 24, which latter has communication with the tank 10 through an inlet opening in the top thereof, preferably at a point remote from the tubular member 13.

Arranged within the cylinder 11 is a piston 25 which is provided with a piston rod 95 26 having an operating handle 27 secured thereto by means of which the operator may reciprocate the piston 25 within the cylinder.

Arranged within the connection 23 between the tubular members 13, 24 is an adjustable nozzle designated generally by the reference numeral 28. This nozzle comprises a casing having a passage 29 therein, which communicates with and forms a continuation of the tubular connection 23. 105 Slidably mounted in the casing 28 of the discharge nozzle is a combined nozzle and valve 30 which is provided with a transverse passage 31, and which passage is adapted to be normally held in a position 110

to register with the passage 29 by means of a suitable elastic member 32 situated within in the casing 28 and engaging the valve 30, so that in the event of the operation of the 5 pump when no receptacle is in position to receive the liquid from the nozzle, the liquid will not be discharged from the nozzle but will flow back into the tank and thereby prevent waste of the liquid. This valve is 10 provided with a tubular portion or nozzle 33 below the passage 31 and arranged within in the tubular portion is a partition 34 to divide the nozzle into two passages 35, 36, one of which, preferably the passage 35, is 15 of a diameter somewhat larger than the diameter of the passage 36. The nozzle 33 is provided with an aperture 37 adjacent but out of communication with the passage 31, which extends through the wall thereof and 20 communicates with the passage 35. A similar aperture or opening 38 is provided on the other side of the partition 34, preferably adjacent the aperture 37 and communicates with the passage 36. The valve 30 is adapt- 25 ed to be moved upwardly against the tension of the elastic member 32 into the position shown in Fig. 2, so as to move the passage 31 out of register with the passage 29 and cause the apertures 37, 38 to register 30 with the passage 29.

The nozzle or tubular extremity of the valve 30 is adapted to slide through a suitable stuffing box 39 and is provided with a circumferential projection 40 secured there- 35 to beyond the stuffing box. This projection 40 may be provided with a circumferential depending flange 41, and arranged within the flange 41 is a suitable packing 42.

Supported in any desired or suitable manner adjacent the discharge nozzle is a bracket 43 which is preferably adjustably secured to the upright tubular member 24 and is provided with a bearing 44 through which the stem 45 of a platform or support 46 is 40 adapted to slide. The bearing 44 is pref- 45 erably bifurcated, as at 47, and extended as at 48 to form spaced ears between which an operating handle or lever 49 is pivotally supported, as at 50. One extremity 51 of the 50 handle 49 projects below the stem 45 of the platform 46 and engages the extremity thereof so that when the handle 49 is depressed, the platform will be raised.

The receptacle to be filled, such as an oil 55 can 52, is adapted to be supported upon the platform 46, as shown in Fig. 1, and is so positioned that when the handle 49 is depressed the oil can will be moved from the position shown in full lines in Fig. 1, 60 to the position shown in dotted lines. As the oil can or receptacle is elevated, the extremity of the nozzle or valve will enter the opening in the top thereof, as shown in Fig. 4, so that the neck of the can will en- 65 gage the packing 42 upon the projection 40.

A further depression of the handle or lever will raise the can or receptacle 52, and with it the discharge nozzle and valve 30 to force the latter upwardly against the tension of the elastic member 32 to move the passage 70 31 out of register with the passage 29 and the passages 37, 38 into register with the passage 29 to the position shown in Fig. 2 of the drawing. When in this position the piston 25 may be reciprocated in the cylinder 11. The upward movement of the piston 25 will unseat the valve 20 and will also draw the oil from the tank 10 through the tubular member 18 and through the passage 21 into the cylinder 11. As the oil flows into the cylinder 11, the valve 20 will be forced against the seat 22 to close the communicating passage 53. When the piston 25 is forced downwardly in the cylinder, the pressure of the oil will seat the valve 20 80 and the oil will also flow through the communicating passage 53 to unseat the valve 19 and be discharged through the tubular member 13 into the tubular member 23 through the opening 37 and the passage 35 in the 85 nozzle to be discharged into the can or receptacle 52. This operation will be continued and the oil will flow into the can until the can has become filled, the oil being prevented from escaping from the can 90 through this opening by means of the packing 42 and projection 40, which form a closure for the can. Any further operation of the piston 25 in a downward direction will create a pressure upon the oil in the can 95 52, and will force the surplus oil into the passage 36, out of which passage it will flow through the opening 38 to be discharged back into the tank. The can or receptacle 100 having been filled, may be removed from the nozzle by raising the handle 49, which will lower the platform 46, and as the can or receptacle moves downwardly, the elastic member 32 will expand to force the valve 30 and the tubular extremity or nozzle 105 downwardly with the can or receptacle to cause the passage 31 to again move into register with the passage 29 to reestablish communication between the tubular members 13 and 24. When this communication has been 110 reestablished, it will be apparent that any operation of the piston 25 to force the oil from the tank 10 into the tubular member 13 will cause the oil to flow through the passages 29 and 31 into the tubular member 24, 115 and be discharged back into the tank, the only effect being to create a circulation of the oil without discharging any of the oil.

The modified form of valve and nozzle as shown in Fig. 3 is particularly adapted for 120 use when the oil supply is fed by gravity and comprises a body or valve 31^a having a tubular portion within which is a partition 34^a to divide the same into two passages 35^a—36^a, which are provided respectively 125 130

5 with openings 37^a, 38^a adapted to register with the passage 29. With this form of valve and nozzle the passage 29 is normally closed, but when the valve is unseated in the manner described, the openings 37^a, 38^a will be moved to register with the passage 29. When the can or receptacle is filled and removed the valve will automatically close to shut off the supply.

10 6 Any suitable means may be provided for limiting the movement of the combined valve and nozzle, and for this purpose there may be provided a slot 54 in the valve and a screw bolt 55 is tapped through the casing 15 28 to extend into the slot and with its head 56 against the outside of the casing.

20 7 The tank 10 may be filled in any suitable manner, but preferably through an opening 57 in the top thereof below the discharge nozzle, and removably arranged within this opening is a strainer 58. This opening also serves as a means whereby any oil which may be spilled from the can or nozzle will be discharged back into the tank.

25 8 In order that the invention might be fully understood the details of the foregoing embodiment thereof have been thus specifically described, but

9 What is claimed as new is—

30 1. In a device of the class described, the combination of a dispensing tank provided with a discharge outlet, a valve connected to the outlet, said valve having a discharge outlet and an independent passage, both 35 adapted to be moved into and out of communication with the tank discharge outlet, means tending normally to adjust the valve to move its outlet out of communication with the tank outlet and the independent 40 passage into communication with the tank outlet, a receptacle support for positioning and holding a receptacle out of engagement with the nozzle, and means for adjusting the support to bodily adjust the receptacle 45 into engagement with the nozzle whereby the latter will be shifted by the adjustment of the receptacle to move the outlet thereof to establish communication of the said outlet with the tank outlet and against the tension of the first recited means.

50 2. In a device of the character described, the combination of a dispensing tank provided with a discharge outlet, a combined discharge nozzle and non-rotatable valve connected to the outlet for discharging the liquid into a receptacle, means tending normally to adjust the valve to close the nozzle, means whereby the valve may be adjusted by a receptacle which is being filled to open 55 the nozzle, and means whereby the liquid will flow through the valve and nozzle and be discharged back into the tank when the said receptacle is filled.

60 3. In a portable device of the character described, the combination of a tank pro-

vided with an outlet for discharging the liquid into a receptacle and an inlet, said outlet and inlet being connected by a pipe, a combined non-rotatable valve and discharge nozzle arranged in the pipe, said 70 valve being provided with a passage, resilient means tending normally to cause the valve to close the outlet of the nozzle and to cause the passage in the valve to communicate with the first said pipe, means 75 whereby the excess liquid will be discharged from the receptacle which is being filled through the nozzle and back into the tank when the receptacle is full.

4. In a portable device of the character 80 described, the combination of a tank provided with an outlet for discharging the liquid into a receptacle and an inlet, said outlet and inlet being connected by a pipe, a combined non-rotatable valve and discharge nozzle arranged in the pipe, said 85 valve being provided with a passage, means tending normally to cause the valve to close the outlet of the nozzle and to cause the passage in the valve to communicate with the first said pipe, means whereby the receptacle which is being filled will adjust the valve to open the nozzle, and means whereby the excess liquid will be discharged through the nozzle and back into the tank. 95

5. In a portable device of the character described, the combination of a tank provided with an outlet and an inlet, said outlet and inlet being connected by a pipe, a combined non-rotatable discharge nozzle and 100 valve arranged within the pipe, said valve having a passage, means tending normally to cause the passage in the valve to communicate with the first said pipe, and to close the nozzle, an adjustable receptacle 105 support, means for adjusting the support and a receptacle thereon to open the nozzle to permit the liquid to be discharged into the receptacle, and means for discharging the excess liquid back into the tank when 110 the receptacle is full.

6. In a device of the character described, the combination of a tank, a pipe leading from the tank and discharging back into the tank, means for forcing the liquid from the tank and through the pipe, a discharge nozzle in the pipe, means for normally closing the nozzle and maintaining a direct passage for the liquid through the pipe and past the nozzle, and means for closing 115 the said direct passage and opening the nozzle to permit the liquid to discharge through the nozzle.

7. In a device of the character described, the combination of a tank, a pipe leading from the tank and discharging into the tank, means for forcing the liquid from the tank and through the pipe, a discharge nozzle in the pipe, means for normally closing the 120 nozzle and maintaining a direct passage for 130

- the liquid through the pipe and past the nozzle, means for closing the said direct passage and opening the nozzle to permit the liquid to discharge through the nozzle and into a receptacle, and means whereby the excess liquid will be discharged back into the tank, the said nozzle-closing means being adapted for automatically reestablishing said direct passage through the pipe.
8. In a device of the character described, the combination of a tank, a pipe leading from the tank and discharging into the tank, means for forcing the liquid from the tank and through the pipe, a discharge nozzle in the pipe, means for normally closing the nozzle and maintaining a direct passage for the liquid through the pipe and past the nozzle, means for closing the said direct passage and opening the nozzle to permit the liquid to discharge through the nozzle and into a receptacle, and means whereby the excess liquid will be returned to the tank when the nozzle is open.
9. In a device of the character described, the combination of a tank, a pipe leading from the tank and discharging directly back into the tank, a movable discharge nozzle in the pipe adapted to project into a receptacle, means for forcing the liquid through the pipe, means for positioning the receptacle to the nozzle to permit the liquid to be discharged therethrough and into the receptacle, means for automatically moving the nozzle to close the same when the receptacle is removed and means for permitting the liquid to flow through the pipe and back into the tank when the nozzle is closed.
10. In a device of the character described, the combination of a tank, a direct pipe leading from the tank and discharging back into the tank, a combined discharge nozzle and non-rotatable valve, means for holding the nozzle normally out of communication with the pipe, and means for moving the nozzle by a vessel to be filled to communicate with the pipe and to interrupt the said direct passage, said nozzle being automatically moved out of communication with the pipe when the receptacle is removed to reestablish the direct passage.
11. In a device of the character described, the combination of a casing having a passage therethrough, a valve movable across the passage to control the same, said valve being provided with a passage adapted to register with the passage through the casing, said valve being also provided with a tubular portion projecting beyond the casing to form a discharge nozzle, means tending normally to hold the passage in the valve in register with the passage in the casing, and to close the said nozzle, said nozzle being provided with an opening adapted to register with the inlet passage in the casing and an opening adapted to register with the outlet passage, and means for moving the valve and nozzle by the engagement therewith of the vessel to be filled to close the passage through the valve.
12. In a device of the character described, the combination of a casing having a passage therethrough, a valve movable across the passage to control the same, said valve being provided with a passage adapted to register with the passage through the casing, said valve being provided with a tubular portion projecting beyond the casing to form a discharge nozzle, means tending normally to hold the passage in the valve in register with the passage in the casing and to close the said nozzle, said nozzle being adapted to be projected into a receptacle and being provided with an opening, means whereby the receptacle will move the nozzle to cause the opening therein to register with the passage in the casing when the receptacle is in position to permit the liquid to be discharged therein, and means whereby the excess liquid discharged into the receptacle will flow back into the tank.
13. In a device of the character described, the combination of a casing having a passage therethrough, a valve movable across the passage to control the same, said valve being provided with a passage adapted to register with the passage through the casing, said valve being also provided with a tubular portion projecting beyond the casing to form a discharge nozzle, means tending normally to hold the passage in the valve in register with the passage in the casing and to close the said nozzle, said nozzle being adapted to be projected into a receptacle and being provided with an inlet opening, means whereby the positioning of the receptacle will move the nozzle to cause the said opening to register with the passage in the casing when the receptacle is in position, to permit the liquid to be discharged therein, and means whereby the excess liquid will be discharged from the receptacle through the nozzle and back into the tank.
14. In a device of the character described, the combination of a casing having a passage therethrough, a valve arranged to control the passage, said valve being provided with a tubular extremity forming a nozzle, said extremity being provided with a partition to divide the same into two passages, one of said passages being provided with an inlet and the other with an outlet, means for adjusting the valve longitudinally to cause the said inlet and outlet of the passages in the nozzle to communicate with the passage in the casing, and resilient means for automatically moving the passages in the nozzle out of communication with the passage in the casing when a vessel to be filled is removed.
15. In a device of the character described, the combination with a casing having a pas-

5 sage therethrough, a valve having a passage movable into and out of communication with the first said passage, means tending normally to hold said passages in communication, said valve being provided with a portion projecting beyond the casing and having two separate passages, one of the passages having an inlet opening, the other passage having an outlet opening, and means for automatically moving the valve longitudinally to place the first said passage in the valve out of communication with the passage in the casing and the said inlet and outlet opening of the projecting portion of 10 the valve into communication with the passage in the casing.

15 16. In a device of the character described, the combination with a casing having a passage therethrough, a longitudinally movable valve having a passage movable into and out of communication with the first said passage, a spring tending normally to hold said passages in communication, said valve being provided with a portion projecting beyond 20 the casing and having a passage normally out of communication with the passage in the casing, means for moving the passage in said portion into communication with the passage in the casing for discharging liquid 25 into a receptacle, and means for discharging the surplus liquid from the receptacle when the latter is full, the last said means comprising a restricted passage through the valve having communication with the receptacle and being simultaneously moved into 30 communication with the passage in the casing with the other passage in the valve.

35 17. In a device of the character described, the combination with a casing having a passage therethrough, a valve bodily movable in the direction of its length having a passage movable into and out of communication with the passage in the casing, said valve being provided with a portion projecting beyond the casing and having a second passage 40 normally out of communication with the passage in the casing, means for moving the valve so that the said second passage is in communication with the passage in the casing for discharging liquid into a receptacle, means for discharging surplus from the receptacle back into the tank, and a spring 45 tending normally to hold the first mentioned valve passage in communication with the casing passage and for automatically moving the said second passage out of communication with the first said passage and simultaneously moving the first said passage in the valve into communication with the passage 50 in the casing.

55 18. In a portable device of the class described, the combination of a tank provided with an outlet for discharging the liquid into a receptacle and an inlet, said outlet 60 and inlet being connected by a pipe, a

bodily movable combined valve and discharge nozzle arranged in the pipe, said valve being provided with a passage, a spring tending normally to move the valve lengthwise to cause the valve to close the outlet of the nozzle and to cause the passage in the valve to communicate with the first said pipe, means whereby the excess liquid will be discharged from the receptacle and through the nozzle back into the tank when the receptacle is full. 70 75

19. In a device of the class described, the combination of a tank, a casing having a passage therethrough provided with an inlet and an outlet, a pipe leading from each of the said inlet and outlet and communicating with the tank, a valve movable in the casing and across the pipe between the said inlet and outlet for controlling the passage of fluid, said valve being bodily movable 80 and provided with a passage and extending beyond the casing to form a discharge nozzle, means tending normally to move the valve to close the last said passage, means whereby the valve may be bodily moved 85 against the tension of the last said means by the engagement of the nozzle with the receptacle to be filled to open the nozzle, and means forming communication with the outlet of the casing and the pipe leading 90 therefrom for discharging excess liquid 95 back into the tank.

20. In a device of the class described, the combination of a tank, a casing having a passage therethrough provided with an inlet and an outlet, a pipe leading from each of the said inlet and outlet and communicating with the tank, a valve movable in the casing and across the pipe between the said inlet and outlet for controlling the passage, 100 said valve being bodily movable and provided with a passage and extending beyond the casing to form a discharge nozzle, means tending normally to bodily move the valve to close the last said passage, means whereby the valve may be moved against the tension of the last said means by the engagement of the nozzle with the vessel to be filled to open the nozzle, means forming communication with the outlet of the casing and the passage leading therefrom for discharging excess liquid back into the tank, and means for causing a circulation of the liquid from the tank and into the first said pipe. 110 115

21. In an apparatus for filling vessels, the combination of a casing having a passage therethrough, a longitudinally movable spring-pressed valve disposed in said casing movable transversely in said passage 125 and formed with a discharge nozzle having a flanged portion, and a vessel support movable to engage the edges of the opening of the vessel to be filled with said flanged portion and thereby to move the valve trans- 130

versely of said passage to open the valve to discharge liquid into the vessel.

22. In an apparatus for filling vessels with liquid, the combination with a casing having a passage therethrough of a spring-pressed longitudinally movable valve disposed in said passage formed with a partitioned tubular discharge nozzle having a flanged portion adjacent the end thereof, a vessel support, and means to move the vessel support, to contact the edge of the opening of a vessel disposed thereon with the said flanged portion whereby the valve is opened by longitudinal movement thereof to discharge liquid automatically through one passage of the nozzle into the vessel.

23. In an apparatus for filling vessels with liquid, the combination with a casing having a passage therethrough of a spring-pressed longitudinally movable valve disposed in said passage formed with a partitioned tubular discharge nozzle having a flanged portion adjacent the end thereof, a vessel support, and means, to move the vessel support to contact the edge of the opening of a vessel disposed thereon with the said flanged portion whereby the valve is opened by longitudinal movement thereof to discharge liquid through one passage of the nozzle into the vessel, the surplus liquid being returned automatically through the passage in said casing through one passage of the partitioned nozzle when the vessel to be filled is full.

24. In an apparatus for filling vessels with liquid, the combination of a casing having a

substantially continuous passage, the ends of which have connection with a common receptacle, of a valve disposed in said passage adapted to be moved transversely with respect thereto, said valve being formed with a partitioned discharge nozzle having holes through the outer shell on diametrically opposite sides of the shell communicating with the two passages formed therein, said holes being adapted to register simultaneously with the passage on both sides of the valve and the lower end of the shell being provided with a flange, a vessel support, and means to move the vessel support so that a vessel thereon may be moved to contact the edges of its fill opening with said flange whereby the partitioned nozzle extends through the fill opening of the vessel and by the continued movement of said means to move the valve so that the holes in the shell thereof register with the passage in the casing, the valve being effective to discharge liquid from one portion of the passage into the vessel to be filled until it is filled and thereafter to discharge liquid through the valve and through the other portion of said passage.

In testimony whereof I have signed my name to this specification, in the presence of two subscribing witnesses, on this 8th day of January, A. D. 1909.
